UNITED STATES PATENT OFFICE.

THOMAS ELLIOTT, OF CINCINNATI, OHIO, ASSIGNOR TO THE CINCINNATI CAR COMPANY, OF CINCINNATI, OHIO, A CORPORATION OF OHIO.

WINDOW GUARD.

Application filed March 20, 1922. Serial No. 545,076.

To all whom it may concern:

Be it known that I, THOMAS ELLIOTT, a citizen of the United States, residing at Cincinnati, in the county of Hamilton and State of Ohio, have invented certain new and useful Improvements in Window Guards, of which the following is a specification, reference being had therein to the accompanying drawing.

10 This invention relates to an improved adjustable window guard for use in railway cars, particularly street and interurban cars.

The object of the invention is to provide 15 a window guard which is easily applicable to a car as regards the fixed features and readily insertable and adjustable as regards the guard proper.

These objects I carry into effect by the structure and arrangement of parts herein- 20 after more fully described.

In the accompanying drawings:

Fig. 1 is a side elevation of so much of a railway car as comprises one window and parts of two adjacent windows with my improvements applied thereto;

Fig. 2 is a vertical section on the line 2—2 of Fig. 1 and looking in the direction of the arrow;

Fig. 3 is an enlarged sectional view on the line 3—3 of Fig. 1 and looking in the direction of the arrow;

Fig. 4 is a partial side view and section on an enlarged scale of a window post, the guide strip and adjacent portions of the guard proper, showing the upper anti-rattler;

Fig. 5 is a like view showing a lower anti-rattler construction;

Fig. 6 is a detail view of the guard proper 40 detached;

Fig. 7 is a detail perspective view of the socket and supporting lugs of the guide strip; and

Fig. 8 is a detail view of the same parts 45 looking from the inside.

So much of a car of any conventional type as consists of the window posts 1, lower sash 2 and upper sash 3 is shown, particularly in Figs. 1 and 3.

To the outer face of the window posts 1 I 50 attach guide strips 4, preferably made of cast aluminum and consisting of an upper section and a lower section, as indicated at 4^a and 4^b in Fig. 1. The upper section comprises a straight strip extending up the win-

dow post 1 from the upper end of the lower section to the top of the window opening, and between such strip and the post a way or guide 5 is formed for the upper sash 3, as seen in Fig. 7. A flange 6 projects inwardly from near the lower end of the section 4^a and forms a rest for the upper sash, as also shown in Fig. 7. Beneath these flanges 6 the section 4^a is fashioned into a three sided socket having a face wall 7 and side walls 8, as best shown in Figs. 7 and 8. Into this socket is fitted the upper end of the lower section 4^b of the guide strip, as indicated in dotted lines in Fig. 1 and clearly shown in Figs. 7 and 8. Webs 9 form 70 braces which support the flanges 6. I have shown two upper sashes in dotted lines in Fig. 8 to illustrate the manner in which the flanges 6 support these sashes.

Screws or other fastenings 10 serve to secure the upper section 4^a to the window post 1.

The lower section of the guide strip is secured to the window post by other screws or fastenings 11 and is formed with a central portion and two wings 12 which embrace the window posts and each of which has vertical flanges 13 to form between them ways or guides within which fit the grating or grill 14 which forms the window guard proper. This guard is shown in full lines in Fig. 1 in its down or normal position and in dotted lines in that figure in raised position. It consists of end members or slides 15 which fit within the ways or guides between the flanges 13 and are capable of being adjusted up and down therein to position the guard proper down or up, as shown in Fig. 1, of intermediate strips 16 and longitudinal rods 17.

I have shown two means of preventing the guard proper from rattling. One consists of spring actuated detents 18 mounted in frames 19 held by rivets 20, the slides 15 being slotted to receive these devices and the tendency of the detent being to press at the point 21 against the adjacent surface of the guide strip 4, as clearly seen in Fig. 4.

This anti-rattle device is located near the upper end of the slides 15 and is effective whether the guard proper be in its lower or upper position.

In order to prevent the lower end of the guard from rattling when in its lower or usual position I incline the guideway in

which the slide 15 travels, as seen at 22 in Fig. 5, and bend the lower end of the slide slightly outward, as seen at 23 in said figure, so that it will impinge tightly against the incline and thus prevent rattling, while not interfering with raising and lowering the guard.

It will now be seen that my invention provides guide strips which perform the double function of maintaining the upper and lower sashes in their proper position with respect to the sash posts and of guides for the window guard proper. And also that the guard may be placed in its lower or usual position or raised to an upper position, as when cleaning the pane in the lower sash or when desired to have the window unobstructed in the lower part of the opening. And further that the guard is held firmly against rattling in the lower position and is sustained in the upper by the pressure detent 18. And also that the upper guide strip not only performs that function for the upper sash but a stop or support therefor through the instrumentality of the flanges 6, and that the upper and lower contiguous strips are interlocked through the socket within the walls 7 and 8, into which the upper end of the lower strip fits.

The whole equipment is simple and strong, is cheaply made and easily applied and also easily removed should occasion require.

Having thus fully described my invention, what I claim as new and desire to secure by Letters Patent, is:—

1. In a car window structure, the combination with upper and lower guide strips of channel formation, outwardly extending flanges on the lower end of the upper strip adapted to support the upper sash, and a guard proper comprising a grill having end slides adapted to fit in the channel of the lower guide strip.

2. In a car window structure, the combination with upper and lower guide strips of channel formation secured to the sash post, the upper strip having lateral flanges to form supports for the upper sash, said upper strip further provided with a socket in its lower end adapted to receive the lower strip, and a guard proper consisting of rods and bars, the outer bars forming slides adapted to fit in the channel of the lower strip.

3. In a car window structure, the combination with lower strips attachable to the window posts, flanges on said strips to form a channel, and a guard proper comprised of rods and bars, the outer bars forming slides adapted to fit in the channels of said strips and to be adjusted up and down therein.

4. In a car window structure having window posts, the combination of lower guide

strips secured to the post, flanges on the guide strips to provide a channel, a guard proper consisting of rods and bars, outer bars forming slides adapted to fit and travel in said channel, and anti-rattling devices carried by said slides and adapted to engage with a surface of the channel.

5. In a car window structure, the combination with a guide strip having flanges to form a channel, the lower portion of said guide strip being inclined, a guard proper having end slides adapted to fit in said channel, the lower end of said slides being bent outwardly to engage said inclined surface to prevent the guard from rattling.

6. In a car window structure, the combination with an upper guide strip of channel formation, lateral flanges formed on the lower end of said guide strips, and upper sashes adapted to rest upon said flanges.

7. In a car window structure, the combination with an upper guide strip of channel formation, outwardly extending flanges on the lower end of the upper guide strip, said guide strip also provided with a socket in its lower end, and a lower guide strip of channel shape adapted to fit within said socket.

8. In window construction, a frame including side members, a lower sash slidable between said side members, channel shaped guide strips secured to the side members opposite the lower sash and provided at their upper ends with flanges closing the channels, other channel shaped guide strips secured to the side members and resting on top of the first mentioned strips, an upper sash mounted slidably in the upper guide strips, and a grill mounted slidably in the lower guide strips.

9. In window construction, a frame including side members, lower guide strips of channel shape secured to said side members in opposition to each other and provided at their upper ends with seats, upper guide strips arranged above the lower guide strips and having their lower ends resting in said seats, said upper guide strips being also of channel shape and having the lower ends of the channels closed by laterally projecting flanges, a sash slidably mounted in the upper guide strips, and a grill slidably mounted in the lower guide strips.

10. In window construction, a frame including side members, lower guide strips of channel shape secured to said side members in opposition to each other and provided at their upper ends with seats, upper guide strips arranged above the lower guide strips and having their lower ends resting in said seats, said upper guide strips being also of channel shape and having the lower ends of the channels closed by laterally projecting flanges, a sash slidably mounted in the upper guide strips, a grill slidably

mounted in the lower guide strips, said grill including side members having anti-rattling springs interposed between the web portions of the lower guide strips and bearing there against, the lower ends of the grill side members being bent inwardly toward the web portions of the respective channels, and

said web members being taperingly thickened downwardly at their lower ends to be engaged by the bent ends of the grill side members. 10

In testimony whereof, I affix my signature.

THOMAS ELLIOTT.
